UNITED STATES PATENT OFFICE.

WILLIAM BUNTING, JR., OF BOSTON, MASSACHUSETTS, ASSIGNOR TO HENRY C. MEYER & CO., OF NEW YORK, N. Y.

WATER-CLOSET.

SPECIFICATION forming part of Letters Patent No. 255,933, dated April 4, 1882.

Application filed December 17, 1881. (No model.)

To all whom it may concern:

Be it known that I, WILLIAM BUNTING, Jr., of Boston, in the county of Suffolk and State of Massachusetts, have invented certain new and useful Improvements in Water-Closets; and I do hereby declare that the following is a full, clear, and exact description thereof, reference being had to the accompanying drawings, making part of this application.

10 My invention relates to a novel construction of that kind of water-closet contrivance in which the valve through which water is supplied to the bowl or hopper of the closet is operated by the seat; and my invention consists in a particular or specific form of contrivance in which the two push-bars are adapted to adjust themselves to any inequality of the plane or level of the seat, so as to cause the latter to always come to an even bearing on the two, though it may 20 be hinged so or may have warped out of shape so that it would not touch both alike were they each arranged in a fixed relationship to each other as to the level of their upper ends.

To enable those skilled in the art to make 25 and use my invention, I will now proceed to more fully explain the construction and operation of the same, referring by letters to the accompanying drawings, in which—

Figure 1 is a front view of a water closet 30 seat embracing my invention, and Fig. 2 is a bottom view of the same.

At Fig. 1 I have represented the wood-work as if partially broken away, in order to better show the devices located beneath the seat proper of the closet, and in the two figures I have designated the same part of the contrivance by the same letter of reference.

A represents the upper part, and B the supporting side portions, of the closet, while C is 40 the seat proper, hinged, as usual, at its rear-most edge to the rear part of the top A.

To the under side of the top A of the closet, near its front, is secured a metallic stand, e, in which is pivotally hung, as shown, a lever, f, one end of which is coupled by a ball-and-socket joint, at i, to the forward end of a lever, g, which has its fulcrum in a metallic stand, h, (secured 45 to and depending from the under side of A, as

shown,) and the rear end of which is connected by a chain or otherwise to the valve of the supply-cistern of the closet. The other end of lever f is pivoted to the middle portion of an equalizing-bar or self-adjusting arm, m, that is formed or provided at each end with an upwardly-projecting rod or finger, o. The arm or bar m is preferably curved, as shown, (see Fig. 2,) so that its ends are located beneath the front part of the seat proper, C, while its middle pivoted portion lies beneath the front part of the portion A of the closet; and at the localities 50 at which the seat C is supported by the vertical rods or fingers o said seat is provided with metallic bearing-surfaces p p, against which bear the upper ends of the metal fingers o o, all as clearly illustrated.

The operation of the contrivance shown and thus far described will be understood to be as follows: The natural or normal conditions of the parts being such as represented in the drawings, with the rear end of the main lever g elevated and the front edge of the hinged seat C raised up, when the front part of seat C is depressed by the weight of the occupant the bar m (through the medium of its fingers o o, on which said seat rests) is moved down 55 bodily, whereby that end of lever f which is pivoted to m is caused to descend to the same extent as the bar m and seat C. This action of the lever f causes that end of it which is jointed at i to the forward end of main lever g to ascend, and thereby said lever g is elevated at its forward end sufficiently to throw the rear end of g downward far enough to properly actuate the chain or other device which connects the rear end of g with the supply-valve of the 60 closet.

It will be seen that the seat, resting, as it does, at its forward part on the two push-bars or fingers o o, placed a proper distance apart, the weight of the occupant of the seat will always be thrown onto a point in the front of the seat intermediate of the two supporting devices o o, thus avoiding the possibility of any uneven strain on either the seat C or its hinged connections with the closet-top.

It will also be seen that by the use of the

arm *m*, attached merely by the pivotal connection shown to the lever *f*, the fingers or bars *o o* projecting up from the ends of *m* are always free to, and always will, adjust themselves vertically, so that their upper ends will lie in any plane in which the front bearing part of seat *C* will come to an equal bearing on them.

What I claim as new, and desire to secure by Letters Patent, is—

10 The combination, with the seat *C*, the supporting-fingers *o o*, and suitable mechanism for

imparting their descending movement to the valve of the closet, of means for rendering said fingers *o o* self-adjusting to any inequality in or changes of the plane of the said seat, substantially as set forth. 15

In witness whereof I have hereunto set my hand this 14th day of December, 1881.

WM. BUNTING, JR.

In presence of—

LOUIS GIRARDIN,

ROBERT A. SOUTHWORTH.
